Attorney.

UNITED STATES PATENT OFFICE.

CHARLES H. BUETTNER, OF CINCINNATI, OHIO.

PROCESS FOR FIXATION OF NITRATES.

1,368,019.

Specification of Letters Patent.

Patented Feb. 8, 1921.

Application filed March 6, 1919. Serial No. 281,056.

To all whom it may concern:

Be it known that I, CHARLES H. BUETTNER, a citizen of the United States, and a resident of Cincinnati, county of Hamilton, 5 and State of Ohio, have invented a certain new and useful Process for Fixation of Nitrates, of which the following is a full, clear, and exact description, reference being had to the accompanying drawings, forming 10 a part of this specification.

The present invention relates to a process for the fixation of nitrates.

The principal object of my invention is to provide a simple commercial process for the 15 fixation of nitrates.

A further object of this invention is to provide a process for obtaining nitrates having a higher percentage of pure nitrogen than has heretofore been possible, and being 20 therefore comparatively free from impurities.

With this and other objects in view, as will more fully appear from the following detailed description thereof, my new process 25 consists in the several details and operations hereinafter fully described and exemplified in the accompanying drawings.

In the drawings:—

Figure 1 illustrates, in part diagrammatically, the device employed in a preferred 30 mode of applying the present invention.

Fig. 2 illustrates a modified application of my new process.

In the application of the process as illustrated in Fig. 1 of the drawings, the numeral 1 indicates the middle section of a vessel or column, said section being constructed of an electrically conductive material, as for instance, metal. The section 1 may be either 35 rectangular, cylindrical, or of any desired shape, and it is open at both ends. Each of the ends is provided with a groove arranged to serve as a seat for an end section 2, the same being constructed preferably of some 40 electrically non-conductive material such as glass or porcelain. The end sections 2 are secured and held in the grooves of column 1 by any suitable sealing and packing substance 3, so as to render the joints air-tight.

The section 1 of the column is provided 45 with a plurality of electrodes 4, in any desired relative arrangement, it being preferable, however, that same be arranged at different elevations in the column. The electrodes 4, are directed toward a central vertical rod 5, supported in the lower end sec-

tion 2 by means of a rod 6. The rods 5 and 6 are electrically conductive, and the rod 6 is inserted through a plug 7 in the bottom of the section 2, by means of which plug the 60 joint is sealed. A tube 8 is inserted in the upper end section 2 of the column and extends downward into a cupped depression 9 in the upper end of the rod 5. The joint between the tube and section 2, is sealed by 65 means of a plug 10 or other suitable means. The tube 8 is connected by means of a hose or pipe 11, to a tank or other source of water supply 12.

Either one or more of the electrodes 4, 70 contains a passage-way 13 communicating with the interior of the column, and through a pipe 14, with the tank 15, containing a supply of pure nitrogen and oxygen gases under pressure, in the approximate proportion 75 of four parts of nitrogen to one of oxygen. In the illustrated embodiment of the process, I have shown two of the electrodes 4 so connected with the tank 15. Valves 16 control the supply of gases through the pipes 14. 80

The column section 1 is connected by means of a wire 17 to a vibrator 18, the latter receiving current through a transformer 19 from a generator or other source of current 20. The other pole of the vibrator is 85 connected by means of a wire 20 with rod 6. As will be obvious, the current passing through the electrodes 4 to the rod 5 will produce a series of arcs between the electrodes and the rod. 90

The lower end section of the column is provided with an outlet 21, which drains through a pipe 22 into an evaporation tank 23.

With the mechanism above described, the 95 process is carried out in the following manner. The column is supplied with gas from the tank 15. The water from the tank 12 or other source of supply, is provided with a certain percentage of lime, if calcium nitrates are to be produced, the percentage being varied at pleasure, and the water so treated flows through a tube into the cupped depression 9 in the upper end of the rod 5, whence it overflows in a film downwardly 100 along the rod 5, into the bottom of the column. During its passage through the gases, the water is subjected to the action of the electric arcs playing between electrodes 4 and rod 5, which cause a deposit of nitrates 105 in solution therein, and as this action is repeated continuously during the flow of the 110

water downwardly along the rod, the same absorbs a high percentage of the salts, in the present instance, being calcium nitrates. Through the bottom of the column the 5 liquid is drained into the evaporation tank 23 where the water is evaporated, leaving a deposit of nitrates in the tank.

Various modifications of the means for applying the principle of the present process 10 will readily occur to those skilled in the art, the central and fundamental phase of the present invention comprising the subjection of a film or minute particles of water during contact with nitrogen gas to the action of an 15 electric arc or arcs. In Fig. 2 of the drawings I have illustrated one such modification.

In Fig. 2 the numerals 24, 25, 26 and 27 illustrate a series of jars arranged so that 20 each successive jar is disposed on a lower plane than the preceding jar. Each of the jars comprises an upper portion 28 and a lower portion 29, the latter extending upwardly into the portion 28, so as to leave an 25 overflow channel 30 between the two parts. The jars are preferably set in concrete supports 31. Disposed on a higher plane than the jar 24, is a tank 32 arranged to be supplied with fresh water from a pipe, 33, having a valve 34. The tank 32 feeds by means 30 of a pipe 35 into the bottom of the jar 24.

The numerals 36 and 37 indicate tanks arranged to be supplied in any suitable manner with the required gases, the tank 36, for example, may be supplied with pure nitrogen and the tank 37 with pure oxygen. The tanks 36 and 37 feed by means of pipes 38 and 39, controlled by valves 40 and 41, into the bottom of the jar 24 at the rate of approximately one part of oxygen to four parts of nitrogen, through a pipe 42. The pipe 42 extends upwardly into the jar terminating slightly below the upper rim of the wall of the lower portion 6 thereof, and thus 45 slightly below the surface of the water therein, and the terminal thereof forms an electrode 43. The mouth of the jar is sealed and an electrode 44 introduced through the seal terminating slightly above the surface 50 of the water in the jar as shown. The electrodes 43 and 44 are connected as shown by wires 45 and 45^a through a vibrator 46 and transformer 47 with any available source of electric current.

55 The channel 30 of the jar 24 is connected by a pipe 48 with the jar 25, and the terminal of said pipe in the latter jar forms an electrode 43 similar to that in the jar 24. Each successive jar in the series is similarly 60 connected to the preceding jar, as shown, except that for the purpose of illustrating a modified method of introducing the electric arcs, the pipe terminal in the jar 27 is not intended to serve as an electrode. In the 65 jar 27 the electrodes are introduced into the

sides of the jar. Each of the jars is provided with a valve controlled outlet pipe 49, for the purpose of draining the same, if desired. Each jar is also provided with a safety valve 50 for the purpose of taking 70 care of any excess pressure in the jar, should the same arise, thus eliminating danger of explosion. The final jar of the series drains by means of pipes 51 and 52 into an evaporation tank 53. Should the water after leaving the jar 27 not be fully charged with salts in solution the same may be caused to drain into a tank 54, a valve 55 in the evaporation tank line and valve 56 in the line of tank 54 controlling such disposition. From 80 the tank 54, the liquid may be returned by means of a pump 57 to the tank 32.

The operation of the above method of applying the process is as follows:—

Water is supplied to the jar 24 from the 85 tank 32. Gases from the tanks 36 and 47 are supplied to the jar 24, the flow being regulated by valves 40 and 41 to the approximate proportions mentioned. The gases bubble upwardly through the water in the jar, 90 while simultaneously the electric arcs play between electrodes 43 and 44 in the jars; the electrical action of the spark upon the spray and gases, as the latter bubble upwardly between the electrodes, combines the gases and 95 results in a deposit of salts in solution in the water. From the jar 24, the water together with any uncombined gases passes to the jar 25, through pipe 48 in which jar a similar electro-chemical action, supplementing that 100 in the first jar takes place, and the water and gases, if any still are uncombined, proceed gravitatingly and by pressure to the third jar, and thence to the fourth and so on. In the jar 27 the electrical action is 105 similar with the exception that the arcs are horizontal instead of vertical. From the last jar and it will be understood that the series may comprise any desired number of jars, the liquid proceeds gravitationally into 110 the evaporation tank 53 where the water is evaporated leaving only the desired salts. Should it prove desirable, however, to continue the process and further enrich the salt 115 deposits in the water the same may be returned through the tank 54 to the original supply tank 32, after which it again proceeds through the series of jars and absorbs the salt deposits of newly provided gases from the tanks 36 and 37.

Having thus fully described my invention what I claim is new and desire to secure by Letters Patent is;

1. The process for the fixation of nitrates 125 consisting in bringing nitrogen and oxygen gases into contact with water in small quantities and subjecting them to the action of an electric arc.

2. The process for the fixation of nitrates 130 consisting in bringing nitrogen and oxygen

gases into contact with water continuously supplied in small quantities and subjecting them to the action of an electric arc, and the subsequent evaporation of the water from the salts deposited therein by such action.

5 3. The process for the fixation of nitrates consisting in continuously supplying water

and nitrogen and oxygen gases to a sealed vessel, next subjecting gases and water in small quantities to the action of an electric 10 arc, then draining the water from the vessel and finally evaporating the water from the salts deposited therein.

CHARLES H. BUETTNER.
